UNITED STATES PATENT OFFICE

GEORGE M. McCANN, OF NEW CASTLE, DELAWARE

GUN

Application filed March 13, 1931. Serial No. 522,466.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to improvement in guns.

A recent development in the construction of guns resides in the provision of a loose tube or liner, that is, one in which a radial play 10 space provided between the tube and jacket is taken up in firing and is restorable after firing and one in which the tube is free to expand and contract longitudinally.

There are now on hand a large number of 15 guns that are to be remodeled to include a loose tube. In these guns the tube was inserted in the jacket from the front and secured by shrinking and usually in addition by a locking sleeve at the forward end of the 20 jacket.

In the present invention it is proposed to remove the shrunk tube and replace it with a loose or removable tube insertable from the rear of the jacket.

25 In order to allow for free longitudinal expansion and contraction it is necessary to secure the tube at the rear and in the present invention it is proposed to provide a simple and effective securing means which may be 30 conveniently held in place by the breech block operating shaft.

To this and other ends the invention consists in the construction, arrangement and combination of elements described herein- 35 after and pointed out in the claims forming a part of this specification.

A practical embodiment of the invention is illustrated in the accompanying drawing, wherein:

40 Fig. 1 is a longitudinal sectional view of a gun having a removable tube secured in the improved manner.

Fig. 2 is an enlarged sectional view through the securing means.

45 Fig. 3 is a view in rear elevation of the gun, parts being in section.

Fig. 4 is a sectional view on the line 4—4 of Fig. 3.

50 Referring to the drawing by numerals of reference—

There is shown a gun consisting of an internally cylindrical jacket 5, an externally tapered tube 6 freely insertable in the jacket from the rear and having a projecting unsupported forward portion 6a, and a breech ring 7 threaded on the jacket in the usual manner. The breech ring carries a vertically sliding block 8 actuated in opening and closing by a shaft 9 mounted in the breech ring and having a handle 9a.

As seen most clearly in Fig. 2, the outer diameter of the tube is less than the inner diameter of the jacket to establish a radial play space 10 between the tube and jacket. The amount of radial play space increases 55 from rear to front and as a consequence insertion and withdrawal of the liner is facilitated. In this type of gun the powder pressure acts in firing to dilate the tube into contact with the jacket but the play space is restored when the powder pressure is no longer 60 present.

Since the tube is loosely mounted in the jacket and would be free to move rearwardly upon inclination of the gun there is provided a securing means consisting of a cross-pin 11 inserted in an aperture in the breech ring and in a tangential groove 12 in the tube. The groove is slightly larger than the cross-pin 75 the clearance 13 corresponding to the 70 radial play space 10, and also permitting of slight longitudinal movement of the tube relative to the jacket. The longitudinal factor of the clearance 13 is allowed for as shown in Fig. 3, so that when the tube sets 85 backs against the cross-pin, it will be substantially flush with the forward wall 14 of the breech block opening in the breech ring.

The cross-pin is located as far to the rear as possible so as to permit longitudinal expansion and contraction of the tube when in action. As seen in Fig. 1 the cross-pin is positioned substantially directly above the breech block actuating shaft 9. The shaft 9 or the handle 9a thereon, whichever is the 90 more convenient for the purpose of removal, is utilized to carry a retaining member 15 for holding the cross-pin in place. As specifically shown the member 15 is in the form 95 of a lug integral with the shaft 9 and also 100

serving to anchor the usual return chain 15a. In order to reduce the size of the retaining member, the cross-pin 11 is provided with a depending tang 11a which is disposed in a recess 16 in the breech ring and held therein by the overlying retaining member 15. When it is desired to insert or remove the cross-pin it is only necessary to remove the retaining member 15 clear of the tang 11a and this may be done by withdrawing it or rotating it depending on the particular character of the mounting. In any event the task will be a simple one that may be quickly performed.

15 In those guns where the operating shaft is not present, for example in guns using separate loading ammunition and a screw breech block, the retaining member 15 would be attached to the breech ring.

20 As seen most clearly in Fig. 3, the opening 17 provided in the breech ring to permit insertion of a round of ammunition is made of sufficient size to permit passage of the tube.

25 The rear end of the liner is formed with one or more collars, two being shown and designated 18 and 19. These collars abut against annular shoulders 20 and 21 in the jacket and prevent forward movement of the liner relative to the jacket. Opposite keys 22-22 are provided on the liner between the shoulders 20 and 21 of the jacket and by engaging in key ways 23 in the jacket hold the liner against rotational movement relative to the jacket.

30 By increasing the radial play space 10 from rear to front it is possible to make the interior of the packet cylindrical and only the liner need be tapered. In so far as this feature is concerned it is not dependent on the particular type of retaining means.

35 I claim.

40 1. A gun comprising a jacket, a tube within the jacket, the outer diameter of the tube being less than the inner diameter of the jacket to establish a play space, a breech ring on the jacket, a breech block in the breech ring, a block operating shaft carried by the breech ring, a cross-pin insertable in the 45 breech ring above the shaft and loosely engaging the tube, and means carried by the shaft for retaining the cross-pin.

45 2. A gun comprising a jacket, a tube within the jacket, the outer diameter of the tube being less than the inner diameter of the jacket to establish a play space, a breech ring on the jacket, a cross-pin insertable in the breech ring and loosely engaging the tube, and means for retaining the cross-pin.

50 3. A gun comprising a jacket, a tube within the jacket, the outer diameter of the tube being less than the inner diameter of the jacket to establish a play space, a breech ring on the jacket, a cross-pin insertable in the breech ring and loosely engaging the tube.

4. A gun comprising an outer member, a tube within the outer member, the outer diameter of the tube being less than the inner diameter of the outer member, a cross-pin insertable in the outer member and loosely engaging the tube adjacent its rear end, and means for retaining the cross-pin.

5. A gun comprising an outer member, a tube within the outer member, the outer diameter of the tube being less than the inner diameter of the outer member, a cross-pin insertable in the outer member and loosely engaging the tube adjacent its rear end.

6. A gun comprising a tapered tube, a jacket extending over the rear part of the tube, the outer diameter of the tube being less than the inner diameter of the jacket whereby the tube is insertable in the jacket from the rear, and a cross-pin tangentially engaging the rear end of the tube to hold the tube in place.

7. A gun comprising an internally cylindrical jacket and an externally tapered tube insertable in the jacket, the outer diameter of the tube being less than the inner diameter of the jacket.
